DRAFT GEAR

Walter C. Dilg, Hewlett, and George R. Munro,
Harbor Greene, N. Y., assignors to Waugh
Equipment Company, New York, N. Y., a cor-
poration of Maine

Application May 17, 1947, Serial No. 748,734

13 Claims. (Cl. 213—46)

1

This invention relates to draft gears for use on railway rolling stock and is concerned more particularly with a novel draft gear of high capacity, which may be employed in a draft pocket, which is of about ordinary depth but is somewhat shorter and wider than is usual. The new gear preferably includes rubber springs and is so constructed that, under normal operating conditions, the development of free and uncontrolled slack between the coupler and vehicle body is prevented.

The draft gear of the invention in its preferred form comprises a plurality of pairs of cushioning units, each made up of alternate rubber spring and dividing plates. One pair of the units lies within the yoke attached to the coupler shank and the remote ends of the units engage the front and rear ends of the yoke. Other pairs of cushioning units lie outside the yoke at each side thereof and the remote ends of the units of each of these pairs normally engage front and rear stops. The cushioning units of the several pairs are separated by a cross member which extends through the yoke and into the spaces between the stops on opposite sides of the yoke. The rubber spring plates used are metal plates with endless bands of rubber on opposite faces thereof and, by the use of the gear construction described, it is possible to utilize plates, the rubber bands of which have approximately the circular form giving the best results.

When a force, for example, in buff, is applied to the coupler of a vehicle equipped with the new gear, the inward movement of the yoke is initially resisted by the front cushioning unit within the yoke and the two rear units outside the yoke. As the inward movement of the coupler continues, the cross member engages the rear stops, and, thereafter, no further compression of the units outside the yoke can occur, although further compression of the front unit within the yoke is possible. The units outside the yoke are of relatively low capacity, and, with the construction described, these units assist the larger units within the yoke during the initial part of the travel of the gear and are, thereafter, protected against being damaged.

For a better understanding of the invention, reference may be made to the accompanying drawings, in which

Fig. 1 is a longitudinal sectional view on the line 1—1 of Fig. 4, showing one form of the new draft gear installed on a railway vehicle; and

Figs. 2, 3, 4, and 5, are sectional views on the lines 2—2, 3—3, 4—4, and 5—5, respectively, of Fig. 1.

In the drawings, the new draft gear is shown installed on a railway vehicle, in which there is a draft pocket 10 formed by means of a housing 11, which has opposed vertical side walls 12, 13

2

and a rear vertical wall 14. The shank 15 of the usual coupler extends into the front of the pocket and the rear end of the shank is pivotally connected at 16 to a yoke 17 of the vertical type, which lies within the pocket. The opposed lateral walls 12, 13 of the pocket have outwardly offset portions forming pocket extensions 18 closed at their outer ends and defined at their front and rear ends by portions of the walls, which 10 form front and rear stops 19, 20, respectively.

A plurality of pairs of cushioning units are mounted within the pocket with one pair of units lying within the yoke and another pair in each of the pocket extensions. Each of the cushioning units within the yoke consists of a plurality of rubber spring plates 21 arranged in alternation with dividing plates 22, and, in the construction shown, there are three spring plates and two dividing plates in each unit. Each spring plate 20 consists of a metal plate of approximately square shape and having a plurality of concentric endless bands 23 applied to its opposite faces and held in place by sections of the rubber, which pass through openings in the plate and connect 25 like rings on opposite faces thereof. The dividing plates are flat plates of metal of the desired size. Each cushioning unit also includes a follower 24, which has a flat inner face, engaged by the adjacent rubber spring plate, and an outer face curved to fit smoothly against the inner surface of the front or rear end of the yoke.

Each cushioning unit in a pocket extension 35 comprises alternate rubber spring and dividing plates and each rubber spring plate comprises a sheet 25 of metal of generally oblong form, on opposite faces of which are mounted a pair of endless rubber rings 26 of generally oval form. The rubber rings 26 on each face of plate 25 are not concentric but lie in alignment and they are 40 connected through the plate to like rings on the other face thereof. In the construction shown, each cushioning unit in a pocket extension is made up of three rubber spring and two dividing plates and the unit also includes a follower 27, 45 which lies at the outer end of the unit and normally engages one or the other of the stops 19, 20.

The cushioning units of the respective pairs are separated by a cross member 28, which extends through the yoke and has ends lying within the 50 pocket extensions. The central section of the cross member lies between the cushioning units of the pair within the yoke and is engaged on its opposite faces by the rubber spring plates at the ends of the units. The cross member is provided near its ends with cross bars 29, which extend from top to bottom of the member and are provided at their outer ends with aligned projections 30, which extend toward one another and enter recesses 31 at opposite ends of the 55 followers 24. The length of each cross bar is some- 60

what less than the distance between the opposed faces of front and rear stops 19, 20.

At its ends, the cross member is provided with housing sections comprising top and bottom walls 32, which are of the length of the cross bars 29 and have outer faces lying flush with the top of the central section. The housing sections lie within the pocket extensions and the cushioning units within the pocket extensions lie within the housing sections. Each housing section is divided into two parts by a vertical dividing wall 33, which connects and is integral with the top and bottom walls 32. Each dividing wall lies between the pair of cushioning units within the housing section and is engaged by the rubber spring plates at the adjacent ends of the units. The top and bottom walls 32 of the housing sections are provided along their front and rear edges with downward projections 34, which enter recesses 35 in the followers 27.

The yoke is supported from beneath by a carrier bar 36, which extends across the bottom of the housing 11 and is secured by bolts 37 to lateral flanges 38 projecting outwardly from the lower ends of the vertical walls 12, 13. The bolts 37 also secure in place plates 39, which extend inwardly and support the housing sections at the ends of the cross member, and washers 40 between the flanges and the supporting plates 39 properly space the parts. A wear plate 41 may be secured, if desired, on the inner face of the lower longitudinal portion of the yoke in such position that the edges of the plates of the cushioning units and the lower face of the cross member travel along the wear plate in the operation of the gear.

In the normal condition of the gear described, the followers 27 of the cushioning unit in the pocket extensions are in contact with the stops 19, 20 and the top and bottom walls 32 of the housing sections of the cross member are spaced from the stops. Upon the application of a force, for example, in buff, to the coupler, the coupler shank and yoke travel inwardly. A compressing force is applied to the front cushioning unit lying within the yoke and the force is transmitted through the cross member to the cushioning units in the pocket extensions to the rear of the cross member. The inward travel of the coupler shank and yoke continues against the resistance of the three cushioning units mentioned, until the rear ends of the top and bottom walls 32 of the housing sections of the cross member strike the rear stops 20. Thereafter, the cross member is prevented from moving rearwardly, so that no further compression of the units in the pocket extensions takes place and further inward movement of the coupler shank and yoke is resisted only by the front cushioning unit within the yoke.

The action of the draft gear in draft is the same as that above described, except that, during the initial outward travel of the coupler shank and yoke, the rear cushioning unit within the yoke and the front cushioning units in the pocket extensions are compressed. When the ends of the cross member engage the front stops, the further compression of the units in the pocket extensions is prevented and continued outward movement of the coupler shank and yoke is resisted only by the rear cushioning unit within the yoke.

The pairs of cushioning units are preferably installed under effective compression such that, under normal train running conditions, the expansivity of one unit of a pair is equal to the

compressibility of the other. Accordingly, when the rear units, for example, in the pocket extensions are being compressed under normal operating conditions by the application of a force in buff to the coupler, the forward units in the extensions expand an equal amount and, accordingly, maintain their followers 27 against the front stops 19, so that both units have continuous contact with the stops. Similarly, under normal train running conditions, the follower of each unit within the yoke is in continuous contact with the front or rear end of the yoke as the case may be.

The installation of the units in the manner described insures that, under normal train running conditions, no free and uncontrolled slack will develop in the gear. Thus, if, after the application to the coupler of a force in buff, which has caused compression of the front unit within the yoke and the rear units in the pocket extensions, the force in buff changes quickly to one in draft, the forward movement of the coupler shank and yoke will be resisted by the rear unit within the yoke and the front units within the pocket extensions. As the rear unit within the yoke has expanded to maintain contact with the rear end of the yoke and the central section of the cross member and the front units in the pocket extensions have expanded to maintain contact with the dividing walls 33 and the front stops 19, these units begin to offer resistance to the forward movement of the coupler shank and yoke, as soon as that movement starts.

In the use of rubber springs of the type described, it is desirable that the endless rubber rings thereon have approximately a circular form, since, with that arrangement, the rings are less likely to be damaged, when subjected to severe compression. Also, little additional capacity is obtained by using springs, which are long in relation to their width and have rubber rings with rounded ends connected by straight sections. If the new gear included only a single pair of cushioning units with rubber springs, which extend across the pocket and into the pocket extensions, such springs would be likely to be damaged in use and would not provide any substantial additional capacity over rubber springs of a size that would fit wholly within the yoke. By using the cross member with the housing sections entering the pocket extensions and installing the additional spring units in the housing sections, the capacity provided by the units within the yoke is substantially increased, and rubber springs having rubber rings of the desired form may be employed. At the same time, the cushioning units in the pocket extensions are protected against damage by the engagement of the cross member with the stops after an initial travel of the gear. The new gear thus makes possible full utilization of the space within a draft pocket, which is of about the same depth but is somewhat shorter and wider than is usual.

We claim:

1. A draft gear for use in a railway vehicle having a coupler, a yoke attached to the shank of the coupler, and spaced sills defining a pocket into which the yoke extends, the pocket having spaced front and rear stops defining lateral pocket extensions at opposite sides of the yoke, which comprises a cross member within the yoke having ends within the pocket extensions and cross bars inward from the respective ends and separating the pocket extensions from the remainder of the pocket, cushioning units between

opposite faces of the member and the front and rear ends of the yoke, cushioning units within the pocket extensions and between the opposite sides of the ends of the member and the stops, and means on the member engageable alternately with the front and rear stops to limit the movement of the member with the yoke in response to forces in draft and buff, respectively, applied to the coupler.

2. A draft gear for use in a railway vehicle having a coupler, a yoke attached to the shank of the coupler, and spaced sills defining a pocket into which the yoke extends, the pocket having spaced front and rear stops defining lateral pocket extensions at opposite sides of the yoke, which comprises a cross member within the yoke having ends within the pocket extensions and cross bars inward from the respective ends and separating the pocket extensions from the remainder of the pocket, cushioning units between opposite faces of the member and the front and rear ends of the yoke, each unit comprising alternate rubber spring and dividing plates, cushioning units within the pocket extensions and between the opposite sides of the ends of the member and the stops, and means on the member engageable alternately with the front and rear stops to limit the movement of the member with the yoke in response to forces in draft and buff, respectively, applied to the coupler.

3. A draft gear for use in a railway vehicle having a coupler, a yoke attached to the shank of the coupler, and spaced sills defining a pocket into which the yoke extends, the pocket having spaced front and rear stops defining lateral pocket extensions at opposite sides of the yoke, which comprises a cross member within the yoke having ends within the pocket extensions and cross bars inward from the respective ends and separating the pocket extensions from the remainder of the pocket, cushioning units between opposite faces of the member between the cross bars and the front and rear ends of the yoke and also between the opposite sides of the ends of the member outside the cross bars and the stops, each unit comprising alternate rubber spring and spacer plates, and means on the member engageable alternately with the front and rear stops to limit the movement of the member with the yoke in response to forces in draft and buff, respectively, applied to the coupler.

4. A draft gear for use in a railway vehicle having a coupler, a yoke attached to the shank of the coupler, and spaced sills defining a pocket into which the yoke extends, the pocket having spaced front and rear stops defining lateral pocket extensions at opposite sides of the yoke, which comprises a cross member within the yoke having ends within the pocket extensions and cross bars inward from the respective ends and separating the pocket extensions from the remainder of the pocket, a pair of like cushioning units within the yoke acting on opposite ends thereof and on opposite faces of the member between the cross bars, pairs of like cushioning units within each pocket extension and outside the adjacent cross bar, the units of each pair acting on opposite sides of one end of the member and on the respective stops at opposite ends of the pocket extension, and means on the member engageable alternately with the front and rear stops to limit the movement of the member with the yoke in response to forces in draft and buff, respectively, applied to the coupler.

5. A draft gear for use in a railway vehicle

having a coupler, a yoke attached to the shank of the coupler, and spaced sills defining a pocket into which the yoke extends, the pocket having spaced front and rear stops defining lateral pocket extensions at opposite sides of the yoke, which comprises a cross member within the yoke having ends within the pocket extensions and cross bars inward from the respective ends and separating the pocket extensions from the remainder of the pocket,

10 pairs of like cushioning units within the yoke acting on opposite ends thereof and on opposite faces of the member between the cross bars, pairs of like cushioning units within each pocket extension, the units of each pair acting on opposite sides of one end of the member outside the adjacent cross bar and on the respective stops at opposite ends of the pocket extension, and means on the member engageable alternately with the front and rear stops to limit the movement of the member with the yoke in response to forces in draft and buff, respectively, applied to the coupler, the cushioning units within the yoke being under effective compression such that, under normal train running conditions, each unit

25 maintains continuous contact with one end of the yoke and one face of the cross member.

6. A draft gear for use in a railway vehicle having a coupler, a yoke attached to the shank of the coupler, and spaced sills defining a pocket

30 into which the yoke extends, the pocket having spaced front and rear stops defining lateral pocket extensions at opposite sides of the yoke, which comprises a cross member within the yoke having ends within the pocket extensions and cross bars inward from the respective ends and separating the pocket extensions from the remainder of the pocket, a pair of like cushioning units within the yoke acting on opposite ends thereof and on opposite faces of the member be-

35 tween the cross bars, pairs of like cushioning units within each pocket extension, the units of each pair acting on opposite sides of one end of the member outside the adjacent cross bar and on the respective stops at opposite ends of the

40 pocket extension, and means on the member engageable alternately with the front and rear stops to limit the movement of the member with the yoke in response to forces in draft and buff, respectively, applied to the coupler, the cushioning units within the yoke being under effective compression such that, under normal train running conditions, each unit maintains continuous contact with one face of the yoke and one face of the member, and the cushioning units in the

45 pocket extensions being under effective compression such that, under normal operating conditions, each unit maintains continuous contact with a side of one end of the member and one of the stops.

60 7. A draft gear for use in a railway vehicle having a coupler, a yoke attached to the shank of the coupler, and spaced sills defining a pocket into which the yoke extends, the pocket having spaced front and rear stops defining lateral pocket extensions at opposite sides of the yoke, which comprises a cross member within the yoke having ends within the pocket extensions and cross bars inward from the respective ends and separating the pocket extensions from the remainder of the

65 pocket, cushioning units between opposite faces of the member between the cross bars and the front and rear ends of the yoke, each unit including a group of alternate spring and dividing plates and a follower between the group and the end of the yoke, cushioning units between oppo-

site sides of the ends of the member outside the cross bars and the stops, each unit including a group of alternate spring and dividing plates and a follower between one end of the group and one of the stops, and means on the member engageable alternately with the front and rear stops to limit the movement of the member with the yoke in response to forces in draft and buff, respectively, applied to the coupler.

8. A draft gear for use in a railway vehicle having a coupler, a yoke attached to the shank of the coupler, and spaced sills defining a pocket into which the yoke extends, the pocket having spaced front and rear stops defining lateral pocket extensions at opposite sides of the yoke, which comprises a cross member within the yoke having ends within the pocket extensions and cross bars inward from the respective ends and separating the pocket extensions from the remainder of the pocket, cushioning units between opposite faces of the member between the cross bars and the front and rear ends of the yoke, each unit including a group of alternate spring and dividing plates and a follower between the group and the end of the yoke, cushioning units between opposite sides of the ends of the member outside the cross bars and the stops, each unit including a group of alternate spring and dividing plates and a follower between one end of the group and one of the stops, means on the member engageable alternately with the front and rear stops to limit the movement of the member with the yoke in response to forces in draft and buff, respectively, applied to the coupler, and means on the member engageable with the several followers and causing each follower to move with the member after an initial movement of the member away from the follower.

9. A draft gear for use in a railway vehicle having a coupler, a yoke attached to the shank of the coupler, and spaced sills defining a pocket into which the yoke extends, the pocket having spaced front and rear stops defining lateral pocket extensions at opposite sides of the yoke, which comprises a pair of cushioning units within the yoke respectively engaging the front and rear ends thereof, a pair of cushioning units in each pocket extension respectively engaging the stops at the ends of the pocket extension, and a cross member extending through the yoke and lying between and engaging the adjacent ends of the units of the pairs, the cross member having portions overlying the units in the pocket extensions and engageable with the stops alternately, a force applied to the coupler initially causing compression of one unit of the pair within the yoke and simultaneous compression of the other units of the pairs within the pocket extensions, the compression of said other units of the pairs within the pocket extensions being terminated upon the engagement of said portions of the cross member with the stops.

10. In a draft gear for use in a railway vehicle having a coupler, a yoke attached to the shank of the coupler, and spaced sills defining a pocket into which the yoke extends, the pocket having spaced front and rear stops defining lateral pocket extensions at opposite sides of the yoke, the combination of a pair of cushioning units adapted to be mounted within the yoke in engagement with the front and rear ends thereof, respectively,

a pair of cushioning units adapted to be mounted in each pocket extension with the units of the pair engaging the front and rear stops, respectively, and a cross member lying between the cushioning units of the several pairs and having top and bottom portions overlying the units adapted to be mounted in the pocket extensions and cross bars separating the cushioning units of the first pair from those of the other pairs.

11. In a draft gear for use in a railway vehicle having a coupler, a yoke attached to the shank of the coupler, and spaced sills defining a pocket into which the yoke extends, the pocket having spaced front and rear stops defining lateral pocket extensions at opposite sides of the yoke, the combination of a pair of cushioning units adapted to be mounted within the yoke in engagement with the front and rear ends thereof, respectively, a pair of cushioning units adapted to be mounted in each pocket extension with the units of the pair engaging the front and rear stops, respectively, and a cross member having a central section lying between and in engagement with adjacent ends of the cushioning units of the pair adapted to be mounted within the yoke, and housing sections at its ends, each housing section having parallel top and bottom walls and a central vertical dividing wall connecting the top and bottom walls, each housing section lying within a pocket extension with the cushioning units of the pair in said pocket extension lying between the top and bottom walls of the housing section and on opposite sides of the dividing wall.

12. A cross member for use in a draft gear, in
35 which the member is mounted between pairs of
cushioning units, the member having a central
section adapted to be engaged by such units on its
opposite faces, cross bars at each end of the
central section, top and bottom walls projecting
40 outwardly from the cross bars and, with the lat-
ter forming housing sections, a dividing wall in
each housing section aligned with the central
section and connecting the top and bottom walls,
and projections from the cross bars extending
45 toward one another.

13. A cross member for use in a draft gear, in which the member is mounted between pairs of cushioning units, the member having a central section adapted to be engaged by such units on its opposite faces, cross bars at each end of the central section, top and bottom walls projecting outwardly from the cross-bars and, with the latter forming housing sections, a dividing wall in each housing section aligned with the central section and connecting the top and bottom walls, projections from the outer ends of the top and bottom walls extending toward one another, and projections from the outer ends of the cross bars extending toward one another.
